1

This invention relates to a circuit arrangement for amplifying or generating ultra high-frequency oscillations which comprises a discharge tube having at least a cathode, a signal control electrode, a perforated positive electrode and two further electrodes.

With ultra-high-frequencies the properties of discharge tubes for amplifying and generating oscillations are greatly different from those with lower frequencies. More particularly in amplifying ultra high-frequencies the fact has to be taken into account that a virtual ohmic resistance having a comparatively small value occurs between the control grid and the cathode which resistance exerts a strong damping on the input circuit. The presence of this virtual ohmic resistance is mainly due to two causes.

Primarily the comparatively great transit time of the electrons will involve a phase displacement between the alternating control-grid voltage and the electronic stream passing through the apertures of the control grid, which phase displacement involves an influence current to the control grid. This influence current has a component which is in phase with the alternating control-grid voltage and may be construed as resulting from a virtual ohmic resistance available between the control grid and the cathode. The reciprocal value of this resistance is called transit-time damping or electron damping.

Secondly the natural inductances of the supply conductors to the various electrodes will exhibit a considerable impedance in regard to the oscillations to be amplified, so that high-frequency voltages are set up across these supply conductors, which voltages give rise to currents passing through the natural tube capacities and being in phase with the alternating control-grid voltage. The damping of the input circuit thus caused may be called lead damping.

The electron damping and the lead damping are both about proportional to the square of the frequency of the oscillations to be transmitted. At ultra-high frequencies the input damping resulting from both of these components is usually so strong that the impedance of the resonant circuit inserted in the signal control grid circuit is high relatively to the input resistance of the tube. Therefore, the output impedance of a stage in cascade circuits is practically solely determined

2

by the input resistance of the next stage, so that the attainable amplification per stage substantially corresponds to the product of mutual conductance and input resistance. In order to obtain sufficient amplification at ultra-high frequencies the attempts have consequently to be directed to as high an input resistance and mutual conductance as possible.

- Recently various proposals have been made to 10 reduce the input damping of amplifying tubes. Thus, for instance, the lead damping can be reduced by making use of a tube having two cathode-supply conductors, one of which is inserted in the input circuit, whereas the other is interposed in the output circuit. Another expedient to reduce the lead damping consists in the use of 15 amplifying tubes comprising two push-pull connected amplifying systems whose cathodes are connected by as short a lead as possible.
- 20 A further improvement of the input damping is possible by taking various measures essentially amounting to back-coupling, for instance by inserting an additional inductance in the screen-grid lead. A very suitable method of decreasing 25 the input damping consists in that in a tube having two cathode supply leads the inductance of the cathode supply lead interposed in the output circuit and/or the screen-grid/control-grid capacity is increased artificially.
- 30 For a good effect of the steps referred to above for decreasing the input damping it is always necessary, however, that the tube should have a fairly high mutual conductance. A high mutual conductance is necessary also for generating ultra 35 high-frequency oscillations.

However, in amplifying or generating oscillations having ultra high-frequencies the effective or dynamic mutual conductance occurring is much lower than the static mutual conductance 40 which is more particularly due to the fact that the transit time of the electrons is of the same order of magnitude as the period of the oscillations to be amplified or to be generated.

It has already been proposed to increase the 45 dynamic mutual conductance by connecting the ends of the output impedance respectively to two electrodes which are located in the path of the electrons and whose mutual distance is covered by the electrons in less than half a period of the oscillations to be amplified or to be generated.

However, since it is not possible to give the distance between the said electrodes an arbitrarily small value an improvement can thus be obtained, only in a limited range of frequencies.

The present invention has for its purpose to provide a circuit by means of which a high dynamic mutual conductance can be obtained even with still shorter waves.

According to the invention this is achieved in the circuit of the kind referred to above by choosing the biases, the construction and the mutual distance of the electrodes in such manner that at least substantially all electrons pass through the perforated positive electrode, are reflected by an electrode more remote from the cathode and hence more traverse the positive electrode, whereupon they are either collected or reflected again by an electrode located at the cathode side of the positive electrode.

If the reflected electrons are able to approach the signal control-electrode they may sometimes cause an increased input damping or a decrease in dynamic mutual conductance. Hence, the electrode located at the cathode side of the perforated positive electrode is so positioned and has such a potential that the reflected electrons cannot affect the signal control electrodes. A maximum dynamic mutual conductance is obtained if the biases of the electrodes are so chosen that the time T , which elapses between the moment at which an electron traverses the perforated electrode for the first time and the moment at which the same electron, after reflection, traverses the perforated electrode again amounts to about a whole number of periods of the oscillations to be taken from the circuit. In this case a less positive auxiliary electrode may still be provided before the perforated positive electrode, and the output energy may be taken from the perforated positive electrode and/or from the reflecting electrode and/or from the said auxiliary electrode.

The invention will be more clearly explained by reference to the accompanying drawing wherein Fig. 1 discloses certain tube electrodes and circuit connections which will serve to explain the principle underlying the invention; Fig. 2 shows comparative mutual conductance curves of a pentode used in a conventional circuit and of a tube used in a circuit according to the present invention; Fig. 3 will serve to explain the conditions under which a maximum dynamic mutual conductance occurs; and Figs. 4, 5 and 6 disclose circuit arrangements of various embodiments of the present invention.

Referring first to Fig. 1 there is schematically represented at 10 an electron stream which, being under the control of a signal control electrode 17, passes through the apertures of a perforated positive electrode 11, is subsequently reflected by the electrode 12, which is at cathode potential, and traverses the electrode 11 for the second time. At the cathode side of the electrode 11 is located a screen-grid 13 which is at cathode potential and reflects the returning electrons for the second time. However, the screen grid 13 may also have such a potential that the returning electrons are collected by this grid. The electrode 11 is located about midway between the electrodes 12 and 13.

Fig. 2 shows two graphs illustrating the effect of the invention. The curve I represents the ratio between the dynamic mutual conductance S and the static mutual conductance S_0 as a function of the product fT and holds for a pentode in which the anode has a positive bias and substan-

tially all electrons reach the anode, f representing the frequency of the oscillations to be transmitted and T corresponding to twice the time required by the electrons for wandering from the screen-grid to the anode.

The curve II represents the ratio S/S_0 as a function of the product fT when making use of the invention, T representing the time elapsing between the moments at which an electron passes for the first time and for the second time through the electrode 11. From the curve II it appears that the dynamic mutual conductance is in each instance a maximum when fT corresponds to a whole number. The maximum values of the dynamic mutual conductance far exceed the values that can be obtained by means of a pentode in a normal circuit arrangement and with the first two maxima it also exceeds the static mutual conductance; with the first maxima ($fT=1$) it may, for instance, be about 2.5 times as high. If $fT=1$, the time elapsing between the first and second time the perforated positive electrode is passed by an electron exactly corresponds to one period of the oscillations to be taken from the circuit. Considering that the influence voltage induced in the electrode 11 by the returning electrons is then completely supported by the influence voltage induced in the electrode 11 by the going electrons it will be appreciated that, in effect, a maximum dynamic mutual conductance must occur under these conditions. This will be more fully explained by reference to Fig. 3.

In Fig. 3 the electrodes 11, 12 and 13 are schematically represented. Let it be assumed that an electronic stream controlled by a signal control electrode (not represented) reaches the electrode 13. If the control voltage is a periodic oscillation the electronic stream consists of a series of succeeding concentrations and deconcentrations of electrons whose alternating current component consists of a series of succeeding positive or negative charges. These charges are represented by small circles in the drawing, in which the minus sign denotes a negative and the plus sign denotes a positive charge. It is now to be taken that the charges consecutively pass from the left to the right one behind the other through the electrode 13 so that the time elapsing between the passage of the charges 21 and 22 amounts to half a period and the time elapsing between the passage of the charges 21 and 23 amounts to a whole period of the oscillations to be amplified.

When the charge 21 travels from the electrode 13 to the electrode 12 a positive image charge is induced in the electrode 11 upon traversing the latter which charge at first increases and subsequently decreases again and has a maximum value at the moment at which the charge is at the point denoted by 21'. In the position 21'' the image charge substantially corresponds again to zero and in the position 21''' it assumes again a maximum value. If the time elapsing between the positions 21' and 21''' exactly amounts to one period of the oscillations to be amplified, which is supposed in the drawing, then, at the same moment at which the charge 21 traverses the electrode 11 in a downward direction, the charge 23 will traverse the electrode 11 in an upward direction, will also induce a positive image charge in this electrode and consequently double the charge already available. As a result of the succeeding negative charges 21, 23, 25 and so on, a voltage represented by the curve III in Fig. 3 will appear in the electrode 11.

In the same way it can be explained that the positive charges 22, 24 and so on induce a voltage in the electrode 11, which voltage is represented by the curve IV. The resulting voltage variations, for which are responsible the influence charges at the electrode 11, are represented by the curve V which is the resultant of the curves III and IV. Therefrom it appears that under the supposed conditions the various charges perfectly cooperate so that at first view a four-fold increase in mutual conductance might be expected. Since, however, the dynamic mutual conductance occurring at any moment, such as is indicated by the curve I, is smaller than the static mutual conductance, the dynamic mutual conductance actually occurring under the supposed conditions is also lower, viz., about 2.5 times as high as the static mutual conductance.

As compared with known circuits, in which the obtainable maximum value of the dynamic mutual conductance corresponds at the most to the value of the static mutual conductance, the circuit according to the invention constitutes a great improvement. If, in effect, a definite minimum mutual conductance is required for amplifying ultra high-frequency oscillations a circuit according to the invention permits this minimum mutual conductance still to be attained at a much higher frequency.

Moreover, it appears from the curve II shown in Fig. 1 that even if the period of the oscillations to be amplified is a multiple of the time interval T considerable maxima occur in the mutual conductance. Thus, for instance, if $fT=3$ the dynamic mutual conductance substantially corresponds to the static mutual conductance. Owing to this the minimum wavelength, at which a sufficient mutual conductance is available as yet, is much smaller than with the circuits hitherto known.

Hereinbefore it has been set out how an amplified voltage is set up at the electrode 11, but it will be appreciated that, as an alternative, the amplified oscillations may be taken from any of the electrodes 12 and 13 and that a suitable choice of the transit times permits the amplified oscillations to be taken in push-pull from the electrodes 12 and 13.

Fig. 4 represents an embodiment of the invention which comprises an amplifying tube 15 having a cathode 16, a signal control grid 17, a grid 13, a perforated positive electrode 11 and a reflection electrode 12. The electrodes 12 and 13 are interconnected and connected through a conductor 27 to the cathode. Between the signal control grid 17 and the cathode 16 is supplied a voltage e_g to be amplified having a frequency f . The perforated electrode 11 is connected to the cathode through the intermediary of a resonant circuit 18 tuned to the frequency f and a source of potential 19 by which the electrode 11 is given a positive potential. The electronic stream emitted by the cathode 16 is controlled in intensity in the usual way by the signal control electrode 17, as a result of which there occur concentrations and deconcentrations in the electronic stream which, due to the positive potential of the electrodes 11, travel in the direction thereof. The concentrations and deconcentrations pass through the apertures of the electrode 11 and are reflected owing to the presence of the electrode 12 having cathode potential so that they pass again through the apertures of the electrode 11. When traversing the electrode 11 forth and back the concentrations and decon-

centrations induce influence charges in the electrode 11, the induced charges amplifying each other, owing to the concentrations and deconcentrations passing forth and back, if the time elapsing between the passage in one and in the other direction substantially amounts to a whole number of periods of the oscillations to be amplified. In this case a voltage having the frequency of the voltage supplied to the electrode 17 can be taken from the circuit 18, the mutual conductance then being much higher than in the absence of the electrode 12.

Fig. 5 represents another embodiment of the invention in which the amplified oscillations are not taken from the perforated electrode but are derived in push-pull from the reflecting electrode and the grid 13 located in front of the electrode 11. Furthermore the tube comprises an electrode 29 which is at a positive potential and has for its purpose to collect the electrons after they have passed for the second time through the grid 13, so that they can no longer affect the control grid 17.

A still greater increase in dynamic mutual conductance can be obtained by taking care that the concentrations and deconcentrations of electrons do not traverse once but several times the space between the reflecting electrode and the electrode located in front of the perforated positive electrode.

An embodiment making use of this principle is represented in Fig. 6. In this case a discharge tube is used comprising a cathode 20, an electron-optical focussing device 21, by means of which the beam can be controlled in intensity at the same time, an electron-optical device 23 by which the electron rays are formed into a beam and accelerated, a grid-shaped electrode 11, a reflecting electrode 12 and a second reflecting electrode 12', the electrode system 11, 12, 12' being so located relatively to the electron beam that its axis 22 forms an oblique angle with the direction of the electrodes 11, 12, 12'. Between the electrode 21 and the cathode 20 is supplied a voltage to be amplified e_g having a frequency f so that concentrations and deconcentrations occur in the electronic stream passing through the electrode 11. This electrode is given a positive potential by the battery B. The concentrations and deconcentrations are reflected by the electrode 12 having cathode potential, pass again through the electrode 11, after which they are reflected by the electrode 12' also having cathode potential, pass again through the electrode 11 and so on as indicated by the dash line 24. Finally all electrons reach the positive electrode 11. Owing to the concentrations and deconcentrations passing through the electrode 11 charges will be induced therein all of which support each other if the time elapsing between two moments at which the electrode 11 is passed by an electron is equal to the period of the oscillations to be amplified. The circuit of the electrode 11 comprises a circuit 18 which is tuned to the frequency of the oscillations to be amplified and from which are taken the amplified oscillations. As an alternative, however, the output circuit 18 may be connected between the electrodes 12 and 12' and earth, as shown in Fig. 5, or between one of the electrodes 12 or 12' and earth, in which case the electrode 11 is at cathode potential for high frequency.

What we claim is:

1. A circuit arrangement for amplifying or generating high frequency oscillations comprising an

electron discharge tube having arranged in the order named a cathode, a signal control electrode, a first reflecting electrode, a perforated electrode and a second reflecting electrode, means to couple said first reflecting electrode to said second reflecting electrode, means to maintain said reflecting electrode at cathode potential, and means to apply a positive potential to said perforated electrode, said electrodes being so constructed, arranged and spaced and said positive potential having such value with respect to the cathode that the electrons, at least for the greater part, perform an oscillatory movement through said perforated electrode and within a region defined by said reflecting electrodes to thereby increase the mutual conductance of said tube.

2. A circuit arrangement for amplifying or generating high frequency oscillations, comprising an electron discharge tube having arranged in the order named a cathode, a signal control grid, a reflecting grid, a perforated electrode and a reflecting electrode, means to couple said reflecting grid to said reflecting electrode, means to maintain said reflecting grid and electrode at cathode potential, means to apply a source of positive potential to said perforated electrode and an output circuit interposed between said perforated electrode and the source of said positive potential, said electrodes being so constructed, arranged and spaced and said positive potential having such value with respect to the cathode that the electrons, at least for the greater part, perform an oscillatory movement through said perforated electrode and within a region defined by said reflecting electrodes to thereby increase the mutual conductance of said tube.

3. A circuit arrangement for amplifying or generating high frequency oscillations, comprising an electron discharge tube having arranged in the order named a cathode, a signal control grid, a reflecting grid, a perforated electrode and a reflecting electrode, means to couple said reflecting grid to said reflecting electrode comprising an output circuit coupled between the reflecting grid and the reflecting electrode, means to maintain said reflecting grid and reflecting electrode at cathode potential and means to apply a positive potential to said perforated electrode, said electrodes being so constructed, arranged and spaced and said positive potential having such value with respect to the cathode that the electrons, at least for the greater part, perform an oscillatory movement through said perforated electrode and within a region defined by said reflecting electrodes to thereby increase the mutual conductance of said tube.

4. A circuit arrangement for amplifying or generating high frequency oscillations, comprising an electron discharge tube having arranged in the order named a cathode, a signal control grid, a

reflecting grid, a perforated electrode and a reflecting electrode, means to couple said reflecting grid to said reflecting electrode comprising an output circuit interposed between said reflecting grid and said reflecting electrode, means to maintain said reflecting grid and said reflecting electrode at cathode potential, an electron collecting electrode positioned on the cathode side of and adjacent said reflecting grid, and means to apply a positive potential to said perforated electrode, said electrodes being so constructed, arranged and spaced and said positive potential having such value with respect to the cathode that the electrons, at least for the greater part, perform an oscillatory movement through said perforated electrode and within a region defined by said reflecting electrodes to thereby increase the mutual conductance of said tube.

5. A circuit arrangement for amplifying or generating high frequency oscillations, comprising an electron discharge tube having arranged in the order named a cathode, a signal control electrode, a beam forming and accelerating electrode, a first reflecting electrode, a perforated electrode and a second reflecting electrode, means to couple said first reflecting electrode to said second reflecting electrode, means to maintain said reflecting electrodes at cathode potential, means to apply a source of positive potential to said perforated electrode and an output circuit interposed between said perforated electrode and the source of said positive potential, said electrodes being so constructed, arranged and spaced and said positive potential having such value with respect to the cathode that the electrons, at least for the greater part, perform an oscillatory movement through said perforated electrode and within a region defined by said reflecting electrodes to thereby increase the mutual conductance of said tube.
